FRAME WITH HOLD-DOWN CLIPS AND RELEASE PINS FOR PLACING ELASTIC BANDS AROUND CONTAINER COVERS

Howard A. Doolittle, East Haven, Conn.

Application September 3, 1947, Serial No. 771,994

2 Claims. (Cl. 226—129)

1

This invention relates to an improvement in means for applying covers to boxes or baskets of berries or other small fruits.

It is desirable and in some places compulsory that small fruit for market shall be covered. The best material for covers is sheets of cellophane but difficulty is experienced in securing such covers to the boxes. Rubber bands produce the best results but it has also been difficult to apply them.

The object of this invention is to provide means for holding a cover over and securing the same to a basket, and the invention consists in the construction and arrangement of parts as hereinafter described and particularly recited in the claims.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view of a device for applying covers to baskets and constructed in accordance with my invention;

Fig. 2 is a sectional view on the line 2—2 of Fig. 1 shown as positioned over a filled and covered basket;

Fig. 3 is a sectional view on the line 3—3 of Fig. 1; and

Fig. 4 is a view similar to Fig. 3 of a modified form of band-release.

The device consists of a rectangular frame corresponding in size to the size of the basket with which it is to be used.

Secured to each side wall 10 is a spring-clip 11, the upper end 12 of which is curved inward. In each corner of the frame is a clearance notch 13 in which is located a pin 14. These pins may be formed at the free ends of spring-wires 15 and normally project upwardly beyond the upper edge of the frame.

The spring-wires 15 are of U-shaped form and have their ends opposite the pins 14 rigidly secured to the frame at the corners of the side walls 10. To prevent the free ends of the spring-wires from being displaced outwardly from their normal positions, a staple 16 or other suitable retaining-means is provided, the cross-reach of the staple bridging the respective grooves 13 adjacent the pins 14, and serves to effectively hold the free ends of the spring-wires 15 in their respective grooves.

2

As thus constructed and arranged, the pins 14 may be moved downwardly into their respective grooves 13 by pressing the upper reaches of the spring-wires 15 downwardly to thus bring the outer ends of the pins 14 beneath the upper edge of the side walls 10, for the purpose as will hereinafter appear. The pins 14 in their normal position serve to hold an expanded rubber band 17 extending parallel to the upper edge of the side walls 10 and spaced slightly away therefrom.

A sheet 18 of cellophane or other suitable material is placed over a filled basket 19 and extends down over the rim 20 thereof. The frame is then set over the basket and the clips 11 serve to hold 15 the skirt-portions of the sheet or cover 18 below the rim 20, to thus retain the sheet or cover temporarily in place. The operator has both hands free to depress two of the pins 14 into a position below the upper edge of the side walls 10, as 20 above described, to partially free the rubber band by stripping the latter from the two depressed pins. This stripping is accomplished by the rubber band being prevented from downward displacement by its engagement with the adjacent 25 surface of the side walls 10 while the pins 14 are depressed into the grooves 13 out of holding engagement with the rubber band.

The release of the rubber band 17 from two of the pins 14 will allow the said band to snap 30 inwardly into engagement with the adjacent portions of the basket 19 to thus firmly grip and hold the same portions of the sheet 18 in place. By depressing the remaining two pins 14 in the same manner as the two pins previously described, the 35 band 17 is completely released so that the remaining portion of the said band may snap into holding engagement around the remainder of the basket 19. Upon release of downward pressure on the upper reaches of the spring-wires 15, 40 the pins 14 will automatically move into their normal uppermost positions in readiness to receive a new rubber band.

It will be apparent that as the rubber band is 45 in a position just below the rim 20 of the basket and above the edge of the sheet 18, the latter is firmly secured to the basket by the encircling rubber band. The now-covered basket may be removed from the frame, a rubber band placed in 50 position on the pins 14 and the frame set over another basket with its sheet or cover 18, preparatory to another sequence of operations, as above described.

It is obvious that the pins 14 may be formed otherwise as, for example, as shown in Fig. 4 of 55 the drawings, pins 21 may be formed at the upper

end of a plunger 22 which is normally held in its upper position by a spring 23 and is depressible to release a rubber band, in the manner described in the form of the invention illustrated in Figs. 1, 2 and 3.

With this device, a helper may readily place the rubber bands in position so that all the packer has to do is to set the frame over a basket and depress the pins.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A device for affixing covers to boxes comprising: a rectangular frame, a spring-clip attached to each side of the said frame and extending upwardly and inwardly inside thereof, and a spring-

pin mounted at each corner of the frame and adapted to be depressed below the upper surface of the frame and adapted to hold a rubber band.

2. A device for affixing covers to boxes comprising: a rectangular frame, a spring-clip attached to each side of the frame and extending upwardly and inwardly inside thereof, a slot in the upper surface of the frame at each corner, and a spring-pin mounted at each corner and adapted to be depressed into said slots below the upper surface of the frame and adapted to hold a rubber band.

HOWARD A. DOOLITTLE.
